In Switzerland August 19, 1938

4 Claims. (Cl. 89—34)

The known types of cartridge magazines for firearms have a spiral guide channel for the ammunition which is moved towards the mouth of the magazine by means of a spring-operated magazine follower. A great disadvantage of these known magazines is that when loading the magazine one cartridge after another has to be pressed into the spiral channel of the magazine against the force of a spiral spring and thus a constantly increasing spring pressure has to be overcome each time a cartridge is inserted. Obviously loading under such conditions requires considerable time. Another disadvantage is that the spiral spring is tensioned when the magazine is loaded. This constant tension of the spring causes fatigue therein which often leads to trouble during automatic loading of the firearm. Difficulties are also encountered when it is desired to empty the magazine for any purpose, because each cartridge has to be removed from the magazine individually which necessitates the pressure against the cartridge being lifted each time. The object of the present invention is to avoid the above-mentioned disadvantages and it relates to a magazine for firearms with a guide channel for the ammunition which is moved towards the mouth of said guiding channel by means of a spring controlled magazine follower. A feature of the invention is that a coupling is interposed between the spring and the follower which can be engaged and disengaged. When the magazine is being loaded this coupling is disengaged so that the spring is not tensioned during this operation but is only tensioned later, for example immediately before firing, by engaging the coupling.

An embodiment of the invention is illustrated in the accompanying drawing by way of example.

Figure 1 is a cross-sectional view taken on the line 1—1 of Fig. 2 through the magazine, certain of the parts being shown in elevation;

Figure 2 is a longitudinal sectional view through the same.

Figure 3 is a partial cross sectional view illustrating a construction wherein a pin is used for separating the coupling elements.

Figure 4 is a partial top plan view of the construction shown in Figure 3.

According to Figures 1 and 2 the magazine for automatic firearms is provided with a fixed spiral guiding channel *a* for the ammunition *b*. *c* is a hollow shaft on which sleeve *d* is rotatably mounted. A spiral spring *e* is arranged on the sleeve *d*, the inner end of which is attached to the sleeve *d* whilst the other end thereof is secured to the fixed guiding channel *a*. The hol-

low shaft *c* is provided with a carrier disc *f* on one of its ends and on the other end thereof a toothed half coupling *g* is formed, the other half of which *g*¹ is slidably arranged in the sleeve *d* by means of a pin and slot connection. The half of the coupling *g*¹ is held in engagement with the other half *g* by a spring *i* but it may be retracted out of engagement with the half coupling *g* by means of a pin *r* provided thereon which projects outwards through a slot *s* in the sleeve *d*. This construction is shown particularly in Figures 3 and 4 and the pin *t* slides in bayonet slots *u* to retain the half *g*¹ retracted. On the coupling end of the sleeve *d* a disc provided with a square stud *k* is fixed on which the crank *m* fits. *n* is a bar shaped magazine follower one end of which engages through a radial slot *f*¹ in the disc *f*.

When loading the magazine according to the present invention, the cartridges are introduced successively into the spiral guiding channel *a* until the magazine is in the almost fully loaded position shown in Fig. 1. During this loading operation follower *n*, which was in that portion of the channel nearest to the mouth at the commencement of the loading operation, is rotated by the cartridges, thus rotating the disc *f* and the hollow shaft *c*. This rotating movement however is not transferred to the spiral spring *e* because the coupling *g* and *g*¹ is disconnected, so that the spring is not tensioned. The spiral spring *e* is not tensioned by means of the crank *m* and the coupling *g* and *g*¹ until the loaded magazine drum is ready for use in an automatic firearm *o* as shown in Figure 1. The tensioned spiral spring *e* acts on the follower *n* which moves the cartridge towards the mouth of the guiding channel by means of the sleeve *d*, the coupling *g* and *g*¹, the hollow shaft *c* and the disc *f*.

40 What I claim is:

1. A drum type cartridge magazine comprising a magazine casing having a channel for cartridges, a magazine follower operating in said channel, a rotatably mounted shaft connected to said follower, a sleeve rotatably mounted on said shaft, a spring for placing said follower under tension to eject said cartridges, one end of said spring being secured to said casing and the other end being secured to said sleeve, and 45 means for connecting said shaft and sleeve comprising a coupling element interposed therebetween, spring means maintaining said coupling element normally in engagement with both said shaft and said sleeve and said coupling element being movable relative to both said shaft and

sleeve into a position of disengagement from one thereof, and means for moving said coupling element into said position of disengagement, whereby the magazine may be loaded with cartridges while said spring means is in untensioned position.

2. A drum type cartridge magazine comprising a magazine casing having a channel for cartridges, a magazine follower operating in said channel, a rotatably mounted shaft connected to said follower, a sleeve rotatably mounted on said shaft, a spring for placing said follower under tension to eject said cartridges, one end of said spring being secured to said casing and the other end being secured to said sleeve, and means for connecting said shaft and sleeve comprising a coupling element interposed therebetween, said coupling element being normally in engagement with both said shaft and said sleeve and being movable relative to both said shaft and sleeve into a position of disengagement from one thereof, yielding means for maintaining such engagement, and manually operable means for moving said coupling element into said position of disengagement against the action of said yielding means, whereby the magazine may be loaded with cartridges while said spring means is in untensioned position.

3. A drum type cartridge magazine comprising a magazine casing having a channel for cartridges, a magazine follower operating in said channel, a rotatably mounted shaft connected to said follower, a sleeve rotatably mounted on said shaft, a spring for placing said follower under tension to eject said cartridges, one end of said spring being secured to said casing and the other end being secured to said sleeve, and means for

connecting said shaft and sleeve comprising a coupling element interposed therebetween, spring means maintaining said coupling element normally in engagement with both said shaft and said sleeve and said coupling element being movable relative to both said shaft and sleeve into a position of disengagement from one thereof, and means for moving said coupling element into said position of disengagement, whereby the magazine may be loaded with cartridges while said spring means is in untensioned position, and means for tensioning said spring after said casing has been loaded.

4. A drum type cartridge magazine comprising a magazine casing having a channel for cartridges, a magazine follower operating in said channel, a rotatably mounted shaft connected to said follower, a sleeve rotatably mounted on said shaft, a spring in the casing for placing said follower under tension to eject said cartridges, one end of said spring being secured to said casing and the other end being secured to said sleeve, and means for connecting said shaft and sleeve comprising a coupling element in said sleeve, said coupling element being constantly in engagement with said sleeve and normally in engagement with both sleeve and shaft and being movable relative to both said shaft and sleeve into a position of disengagement from said shaft, yielding means for maintaining such engagement, and manually operable means for moving said coupling element into said position of disengagement against the action of said yielding means, whereby the magazine may be loaded with cartridges while said spring means is in untensioned position.

ANTOINE GAZDA.
